UNITED STATES PATENT OFFICE.

FRED M. LOCKE, OF VICTOR, NEW YORK.

ARC-EXTINGUISHER.

1,116,303.

Specification of Letters Patent.

Patented Nov. 3, 1914.

Application filed March 27, 1912. Serial No. 686,554.

To all whom it may concern:

Be it known that I, FRED M. LOCKE, of Victor, in the county of Ontario, in the State of New York, have invented new and 5 useful Improvements in Arc-Extinguishers, of which the following, taken in connection with the accompanying drawings, is a full, clear, and exact description.

This invention relates to certain improvements in electric arc extinguishers of the 10 class set forth in my pending application #641,536 filed July 31, 1911, in which the arc is instantly broken upon its formation by the blast of an explosive ignited by such 15 arc.

It is well known that in overland transmission of electric current and particularly that of high voltage, the feed wires which are supported at intervals upon suitable 20 insulators usually of high electrical resistance become surcharged with extra current especially during severe electrical storms and that this excess of current in seeking the course of least resistance to the ground 25 is more or less localized at and upon the insulators thereby producing arcs of abnormal size and tension between different portions of the insulator or between such insulator and its supporting arm or pin. Under 30 these conditions it frequently happens that one or more insulators and their supporting pins and cross arms will be burnt out or broken down to such an extent as to short circuit the feed wire to the ground 35 or otherwise, thereby cutting off further distribution of the current. It has been discovered that these arcs form most frequently between the edges of the upper surfaces of the insulator and its supporting arm, and 40 that if some means could be devised for breaking the arc at substantially the same instant that it is formed, the destructive results hereinbefore mentioned would be largely obviated, and the main object of 45 my present invention is to provide simple means for localizing any arc or arcs which may be formed at different points around the edge of the insulator and to utilize the heat developed by the localization of such 50 arc in igniting an explosive and directing the blast across the arc to extinguish the same instantly upon its formation, thereby preserving the integrity of the insulator and its supporting means and also 55 permitting the use of the same receptacle

and terminals for the reception and ignition of an additional explosive charge.

Other objects and uses will be brought out in the following description:

In the drawings—Figure 1 is a side elevation of an insulator and portion of a conductor supported thereon together with the insulator support and a series of my improved arc-breaking devices in operative position around the insulator. Fig. 2 is an elevation of the same insulator, conductor and support showing a plurality of arc breaking devices supported on the cross arm at different points around the insulator in a manner slightly different from that shown 60 in Fig. 1. Fig. 3 is an enlarged sectional view through one of the cartridges and igniting terminals.

These arc extinguishers are adapted to be used in connection with any form of insulator but more especially with the larger insulators adapted to carry the conductors as—*A*—for high potential current and for this purpose I have shown the usual sectional type of insulator—*a*—composed of bell-shaped sections nested one within the other with suitable means as a tie wire—*a'*—for attaching the feed wire—*A*—to the top of the insulator. This insulator is supported upon a suitable central pin—*b*—which is secured in the usual manner to a cross arm—*B*—of a pole or tower not shown.

The upper insulator section to which the feed wire—*A*—is directly secured is of considerably greater surface area than the remaining underlying insulator sections and although it is supported a considerable distance above the cross arm to form a comparatively long intervening air gap to reduce as far as possible any liability of short circuit from the feed wire to the ground through the pole under normal conditions, it is always exposed to the direct action of abnormal charges or surcharges of electricity from the feed wire particularly during electric storms when the highly surcharged current following the feed wire will be localized at the insulator, the surface of which under such conditions is more or less moist, thereby increasing the tendency of the highly surcharged current to arc across such intervening air space to the cross arm and thence to the ground through the pole. This abnormal arcing of the current usually takes place between the outer edges 100 105 110

of the upper insulator section and its supporting pin or cross arm according to the course of least resistance, and frequently results in burning out or breaking down the insulator and its supports and in order to 5 obviate as far as possible these destructive results, I have interposed one or more, in this instance four, sets of electric conductors —1— and —2— in the gap between the 10 uppermost insulator section and cross arm and have connected in each set of conductors a cartridge shell —3— containing an explosive material such as a body of powder —4— and a suitable wad or plug —3'—, the 15 latter serving to retain the powder in the cartridge shell —3—.

As shown in Fig. 1, the conductors —2— converge downwardly and inwardly toward the insulator pin —6— where they are preferably united to each other and supported 20 upon said pin so that the conductors —2— constitute supports for holding the cartridges —3— at different points around the insulator but some distance apart therefore 25 from with their plugged ends pointing toward the arc which may be formed between the conductor and cross arm.

A portion, preferably the bottom at least 30 of the shell —3— containing the explosive —4— is made of electric conducting material as metal and in this instance this metallic portion of the shell is connected directly to the support —2— so as to form one of the 35 ignition terminals for the explosive. The conductor —1— constitutes the other ignition terminal and is permanently secured to an insulated portion —5— of the shell as best seen in Fig. 3, said conductor —1— having its lower end extending into the interior 40 of the shell —3— where it is surrounded by the explosive —4— and is spaced apart from the adjacent end of the other ignition terminal —2— a distance somewhat less than from other points of the metal 45 portion of the shell so as to produce a spark for igniting the explosive. In other words the insulating material —5— at either side of the conductor —1— is of greater width than the distance between the sparking 50 ends of the conductors —1— and —2— so as to quicken the ignition of the explosive instantly upon the formation of any arc which may tend to form between the conductor and insulator or between the insulator 55 and its support. As a further means of causing the instantaneous combustion of the explosive, the conductors —1— are extended upwardly to points in proximity to but separated from the periphery of the uppermost 60 insulator section so as to lie in the path of any arc which may tend to form between the conductor and insulator or between the insulator and its support, thereby inducing the arc to follow the conductors —1— and 65 —2— before reaching the insulator sup-

port, thus igniting the explosive and directing the blast across the arc to extinguish the same instantly upon its formation and before it has time to do any material damage to the insulator or its support.

70

In Fig. 2 I have shown the conductors —2'— corresponding to the conductors —2— as mounted directly upon the cross arm and supporting the cartridge shell —3— in such position as to direct the blast across any arcs which may be formed between the edges of the insulator sections and cross arm. Otherwise the construction of the cartridge and terminals —1— are substantially the same as shown in Figs. 1 and 3. The 80 main features of the invention, however, consist broadly first in positioning the cartridge so as to direct the blast of the explosive into or across any arc which may tend to form between the conductor and insulator or between the insulator and its support; second, to arrange the igniting terminals so as to divert a portion at least of the arc thereto and into the explosive instantly upon the formation of such arc, 90 thereby igniting the explosive and discharging the blast into the arc with sufficient force to extinguish it immediately upon its formation; and third supporting one of the 95 terminal conductors permanently in the cartridge so that the same cartridge and terminals may be reused by refilling the shell with an explosive and inserting a new plug or wad. Further than this, the construction of the cartridge and manner of supporting the 100 terminals may be varied without departing from the spirit of my invention.

What I claim is:

1. In an arc extinguisher, a receptacle containing an explosive material, a conductor having a portion lying adjacent the path of a possible arc and a portion extending within the receptacle and insulated therefrom so that upon the formation of an arc, a spark passing between the conductor 110 and the receptacle will ignite the explosive and thereby extinguish the arc.

2. In an arc extinguisher, a receptacle containing an explosive material, a conductor having a portion lying in the path 115 of a possible arc and another portion extending through a wall of said receptacle and insulated therefrom and in contact with the explosive material, a terminal in connection with said receptacle so that upon 120 the formation of an arc, a spark passing between the conductor and the terminal will ignite the explosive and thereby extinguish the arc.

3. In an arc extinguisher, a receptacle 125 containing an explosive material, a conductor having a portion lying in the path of a possible arc and another portion extending through a wall of said receptacle and insulated therefrom and in contact with 130

the explosive material, a terminal in connection with and forming a support for said receptacle so that upon the formation of an arc, a spark passing between the conductor and the terminal will ignite the explosive and thereby extinguish the arc.

4. In combination with an electric conductor and an insulator support therefor, a receptacle containing an explosive and adapted to discharge in the region of an arc which may be formed between the conductor and the insulator, a conducting member having a portion lying in the path of such possible arc and another portion extending through a wall of said receptacle, a terminal in connection with said receptacle, said conducting member separated from the wall of the receptacle through which it passes by insulating material of greater radius than the distance between said conducting member and said terminal.

5. In an arc extinguisher, a receptacle containing an explosive material, a conductor having a portion lying in the path of a possible arc and another portion extending through a wall of said receptacle, a terminal in connection with said receptacle, said conducting member separated from the wall of the receptacle through which it passes by insulating material of

greater radius than the distance between said conducting member and said terminal.

6. In an arc extinguisher, a receptacle containing an explosive material, a conductor having a portion lying in the path of a possible arc and another portion extending through a wall of said receptacle and insulated therefrom, a terminal in connection with said receptacle so that upon the formation of an arc a spark passing between the conductor and the terminal will ignite the explosive and thereby extinguish the arc.

7. In an explosive cartridge for arc extinguishers, a metal casing closed at one end and open at the other end and having a removable plug in the open end, a conducting member having an exposed portion and another portion extending into the metal casing and insulated therefrom and so positioned that a spark passing between the conductor and the casing will ignite the explosive.

In witness whereof I have hereunto set my hand on this 15th day of March 1912.

FRED M. LOCKE.
